US0D1070870S

(12) **United States Design Patent** (10) **Patent No.:** **US D1,070,870 S**
Moriarty (45) **Date of Patent:** ** *Apr. 15, 2025

(54) **DISPLAY SCREEN WITH GRAPHICAL USER INTERFACE FOR A BUTTON ARRANGEMENT**

(71) Applicant: **William R Moriarty**, Pasadena, CA (US)

(72) Inventor: **William R Moriarty**, Pasadena, CA (US)

(73) Assignee: **LawGood, Inc.**, Los Angeles, CA (US)

(*) Notice: This patent is subject to a terminal disclaimer.

(**) Term: **15 Years**

(21) Appl. No.: **29/774,944**

(22) Filed: **Mar. 19, 2021**

(51) LOC (15) Cl. **14-04**

(52) U.S. Cl.

USPC **D14/485**
